UNITED STATES PATENT OFFICE.

GEORGE E. TRAVIS, OF HENRY, ILLINOIS.

BELT-TIGHTENER.

SPECIFICATION forming part of Letters Patent No. 657,301, dated September 4, 1900.

Application filed January 8, 1900. Serial No. 753. (No model.)

To all whom it may concern:

Be it known that I, GEORGE E. TRAVIS, a citizen of the United States, residing at Henry, in the county of Marshall and State of Illinois, have invented certain new and useful Improvements in Belt-Tighteners, of which the following is a specification.

This invention relates to belt-tighteners for traction-engines, and has for one object to provide improved and simple means for tightening the belt of a thresher-traction while the engine is at work and maintaining the belt taut.

It also has for its object to provide a safety device that will effectually operate to prevent breakage or damage should the belt-tightening mechanism be accidentally thrown into operation while the engine is being propelled as a traction-engine.

It has for a further object to provide a friction-clutch attachment operating in such manner that the clutch-lever holds the clutch out of operation while the belt-tightener is in gear.

To these ends my invention consists in the features and in the construction, combination, and arrangement of parts hereinafter described, and particularly pointed out in the claims following the description, reference being had to the accompanying drawings, in which—

Figure 1 is a view in elevation showing the engine connected to a threshing-machine. Fig. 2 is a sectional side elevation, on an enlarged scale, of the means for throwing the parts into and out of operation. Fig. 3 is a transverse section taken through the frame, idler-wheel, and ratchet. Fig. 4 is a detail perspective view of the frame and the pawl and dog operating mechanism. Fig. 5 is a view in elevation of the latch-lever and link mechanism, and Fig. 6 is a plan view of the clutch-operating hook.

Referring to the drawings, the numeral 1 indicates a traction-engine of any suitable construction, 2 a drive-wheel driven by the engine, and 3 a drive-belt for transmitting power from the engine to the threshing-machine. The drive-wheel 2 may consist of a friction clutch-wheel of any of the well-known types employed for the purpose and adapted to be thrown into and out of operation by a

clutch-lever 4 to engage and disengage the engine-shaft 5 with and from the train of gearing leading to the ground-wheels 6. Said train of gearing is shown as consisting of the idler gear-wheel 7, which meshes with and transfers the movement of the engine-shaft to a gear-wheel 8. The gear-wheel 8 rotates a smaller gear-wheel 9, which in turn gears with and rotates a gear-wheel 10, fixed on the axle of the ground-wheels 6.

Fixed concentrically on the gear-wheel 7 is an annular casing 11, which is preferably bolted to said gear-wheel and is provided with two circumferential grooves 12 and 13, in the former of which is seated a ratchet-wheel 14 and in the latter one end of a frame 15, the other end of which is fixed to the engine-frame or any suitable fixed support. One or more break-pins 16 pass transversely through the casing 11 and ratchet-wheel 14, so that the latter normally rotates with the gear-wheel 7 for the purpose hereinafter explained. Fulcrumed on a pivot 17 on the frame 15 is a hand-lever 18, carrying a gravity-pawl 19, pivoted to said lever near its fulcrum and normally swinging by gravity into engagement with the ratchet-wheel 14. A gravity-dog is pivotally mounted on the pivot-pin 17 and operates to engage the ratchet-wheel 14 and hold the latter against backward movement. The locking-dog 20 is provided with an upward extension 21, by means of which the dog may be thrown out of engagement with the ratchet-wheel 14 in the manner hereinafter explained, and when the dog is so thrown out of engagement it strikes the pawl 19 and throws it also out of engagement with said ratchet-wheel.

If the driving-belt 3 becomes loose, it is only necessary to depress the free end of the hand-lever 18, thus causing the pawl 19 to move the gear-wheel 14 the distance of one tooth, and through the medium of the train of gearing described thereby move the engine a slight distance away from the threshing-machine, thus tightening up the belt to a greater or less extent. This operation may be repeated to move the engine the proper distance to give the proper tension to the belt, and after this has been accomplished the locking-dog 20 will hold the engine stationary and the belt taut.

When the engine is disconnected from the threshing-machine and is to be propelled over the road, it is necessary to throw the pawl and dog out of engagement with the ratchet-wheel 14, and this is accomplished by the following means: Fulcrumed on the pivot-pin 17 is an arm 22, provided with a laterally-projecting lug 23, that is adapted to engage the extension 21 of the locking-dog. Pivoted intermediate its ends to a fixed support 24 is a trip-lever 25, to which is pivotally connected one end of a link 26, the other end of which is in like manner connected to the end of the arm 22. As shown, the pivotal connection 27 between the link and trip-lever is such that when the latter is swung toward the rear of the engine the pivotal point 27 will be in alinement with the fulcrum of the trip-lever and the latter and the link will be held against movement, and the same is true when the trip-lever is swung in the opposite direction. When the trip-lever is swung toward the front of the engine, the link 26 is moved forward and oscillates the arm 22 in the same direction, thereby causing the lug 23 to bear against the extension 21 of the locking-dog and moving said dog and pawl out of alinement with the ratchet-wheel 14. When the trip-lever is swung in the opposite direction, the arm 22 is drawn out of engagement with the locking-dog and the latter and the pawl drop by gravity into engagement with the ratchet-wheel. The trip-lever and link are held in their adjusted positions in the following manner: Formed on the tail of the trip-lever is a laterally-projecting lug 28, which when the said trip-lever is in the position shown in Fig. 1 engages the under side of the link 26 and is caused to press thereagainst by a coiled spring 29, one end of which is attached to the said link and the other end to the frame 15 or other suitable fixture, said spring operating to draw the link downward. Formed on the handle end of the trip-lever is a corresponding lug 30, which in like manner bears against the upper side of the lever when the trip-lever is swung forward to throw the dog and pawl out of engagement. The parts are thus positively locked when in either of the adjusted positions.

If the well-known friction-clutch be employed, as before described, for throwing the engine-shaft into gear with the train of gearing for propelling the engine, I provide a safety attachment that operates to hold the clutch-controlling lever in such manner that the clutch cannot be put in gear while the dog and pawl are in engagement with the ratchet-wheel. The safety attachment is constructed as follows:

The numeral 31 indicates a hook that engages the controlling-lever of the friction-clutch, the shank of said hook being provided with a longitudinal slot 32. Fitted in the slot 32 is a bolt 33, that extends through, and on its end is fitted a corrugated washer 33^a, that engages corresponding corrugations

formed on the shank of the hook. Said washer is held in place by a nut 33^b. By these means the length of the hook may be altered. The arrangement is such that when the link 26 is drawn rearward by the trip-lever to throw the dog and pawl into engagement with the ratchet-wheel the pin 33 draws the hook 31 toward the rear of the engine, thereby drawing the clutch-controlling lever 4 in the same direction and throwing the clutch out of operation. The clutch will be positively held out of operation as long as the dog and pawl are in engagement with the ratchet-wheel. When, however, the link 26 is thrust forward by the trip-lever to throw the dog and pawl out of engagement, the pin 33 rides forward in the slot 32 of the safety-hook, thereby releasing the latter, after which the controlling-lever can be operated at will to propel the engine.

While the engine is being moved over the road should the pawl and dog be accidentally thrown into engagement with the ratchet-wheel or should an abnormal strain be suddenly thrown onto the ratchet-wheel the break-pin 16, before referred to, will break, thereby preventing damage to the gearing, as the ratchet-wheel 14 and gear-wheel 7 are then free to rotate independently. The break-pins may be readily replaced when broken.

If preferred, the ratchet-wheel 14 may be dispensed with and the dog and pawl caused to engage directly with the cog-teeth of the gear-wheel 7.

By means of the dog and pawl described the belt can be put on the drive-wheel and tightened at ease. The belt can be positively tightened to any desired tension little by little and at will and will be held in its tightened condition, thereby holding the engine stationary without the use of blocks for chocking the wheels and holding the engine steady without vibration.

The improvements herein shown and described may be placed on the engine when the latter is built in the factory or may be placed on engines built and in use.

Having described my invention, what I claim is—

1. In a belt-tightener of the character described, the combination with the traction-engine and its train of driving-gearing, of the idler gear-wheels, the pawl and dog engaging a ratchet-wheel fixed on said idler-wheel, the link and arm for throwing said pawl and dog into and out of gear, and the trip-lever for actuating said link and holding it locked against accidental movement, substantially as described.

2. In a belt-tightener of the class described, the combination with the traction-engine and its train of driving-gearing, of the idler gear-wheel, the pawl and dog engaging a ratchet-wheel fixed on said idler-wheel, an oscillating arm for throwing the pawl and dog into and out of engagement, a link connected to said arm, a trip-lever pivoted intermediate its ends

to a fixed support and pivoted on one side of its fulcrum to said link, said trip-lever being provided at its opposite ends with lugs arranged to respectively engage the upper and 5 under side of the link, and a coiled spring operating to draw the link down, substantially as described.

3. In a belt-tightener of the character described, the combination with the traction-engine, its train of driving-gearing and a friction-clutch on the engine-shaft for throwing said gearing into and out of gear, of the idler gear-wheel, the pawl and dog engaging a ratchet-wheel fixed on said idler-wheel, the 10 link and arm for throwing said pawl and dog into and out of engagement, the trip-lever for actuating said link and holding it locked against accidental displacement, a pin on the link, and a safety-hook engaging the control-

ling-lever of the friction-clutch and having a 20 slotted shank engaged by said pin, substantially as described.

4. In a belt-tightener of the character described, the combination with the traction-engine and its train of driving-gearing, of the 25 idler gear-wheel, the ratchet-wheel, a break-pin connecting said ratchet and gear wheel together, a pawl and dog arranged to engage the ratchet-wheel, a lever for actuating the pawl, and means for throwing the pawl and 30 dog into and out of engagement with the ratchet-wheel, substantially as described.

In testimony whereof I have affixed my signature in presence of two witnesses.

GEORGE E. TRAVIS.
